UNITED STATES PATENT OFFICE.

LUDGER E. LA BRIE, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed July 12, 1926. Serial No. 123,289.

This invention relates to brakes, and is illustrated as embodied in a novel shoe for an internal expanding automobile brake. An object of the invention is to provide a light and inexpensive but very strong brake shoe, preferably adapted to overlap an adjacent shoe of the same brake, or if desired to overlap such a shoe at each end.

Having this object in mind, an important feature of the invention relates to forming at least a part of the stiffening web of the shoe, for example at one or both ends where it is desired to overlap the shoes, Y-shaped in cross-section radially of the shoe. That is, the web branches some distance inwardly from the friction portion of the shoe to form a channel-shaped pocket which may overlap the end of an adjacent shoe.

This leaves a very narrow web immediately adjacent the friction face, which does not interfere with riveting the lining to the shoe, and at the same time obviates any necessity of attaching a separate plate or the like across the spaced parts of the web, to support the brake lining.

I prefer to form the shoe of pressed metal, with two flanges engaging each other and jointly forming the above-described stiffening web, and being spread apart to form the branching of the web. Various features of novelty relate to details of this spreading apart of the flanges some distance inside of the friction portion of the shoe.

The above and other objects and features of the invention, including various novel and desirable details of construction, will be apparent from the following description of the illustrative embodiment shown in the accompanying drawing, in which:

Figure 1 is a vertical section, just inside the head of the brake drum, through an automobile brake, showing the novel brake shoes in side elevation;

Figure 2 is a partial section on the line 2—2 of Figure 1, showing the overlapping of two of the shoes;

Figure 3 is a section through the overlapping parts of the shoes, on either of the lines 3—3 of Figure 1 or Figure 2;

Figure 4 is a partial section on the line 4—4 of Figure 1, showing the pivot connecting two of the shoes; and

Figure 5 is a section through any one of the shoes, on any one of the lines 5—5 of Figure 1.

The brake selected for illustration includes a rotatable drum 10, at the open side of which is a support such as a backing plate 12, and within which are arranged three brake shoes 14, 16 and 18, shoes 14 and 18 preferably being interchangeable. Shoe 16 is anchored on a pivot 20 carried by the backing plate, while shoes 14 and 18 are respectively connected to shoe 16 by pivots 22 and 24.

The brake is applied by forcing shoes 14 and 18 apart by means such as a double cam 26, against the resistance of a return spring 28, shoe 16 being forced toward the drum against the resistance of an auxiliary return spring 30 by the shoes 14 and 18 acting through pivots 22 and 24. The idle position of shoe 16 may be determined by an adjustable grooved eccentric 32 interlocking with a flange on the end of pivot 24 and toward which pivot 24 is urged by spring 30.

In the illustrated arrangement each of the shoes 14 and 18 is formed by riveting or spot-welding or otherwise securing back to back two stampings, each having an outer cylindrical flange 34 supporting one side of the brake lining 36, and which have flanges 38 jointly forming the stiffening web of the shoe, and formed with an opening 40 large enough to afford ample clearance for anchor pivot 20, which takes the torque of all three shoes. Integral bearings or bosses 42 may be drawn outwardly on flanges 38 to embrace the several pivots, and flanges 38 may be grooved to form strengthening ribs 44. There may also be short stiffening flanges 46 along the inner edges of the stampings.

The present invention relates to certain features of the brake shoes, as for example shoe 16, whether or not they are used in the particular brake described above. In a general way, shoe 16 may be like shoes 14 and 18 in construction, having the flanges 34 supporting the brake lining 36, and flanges 38 integral therewith and jointly forming the stiffening web of the shoe.

According to an important feature of the invention, however, the flanges 38 of shoes 16,

preferably at the ends of the shoe, after continuing together some distance radially inward (see Figure 3) are spread apart to form spaced portions 50 straddling the end of shoe 14 (or 18). Thus this part of the shoe is Y-shaped in cross-section radially of the shoe, with the stem of the Y immediately adjacent the friction portion 34 of the shoe. This part of the shoe is also Y-shaped in section lengthwise of the shoe in the shoe 16 illustrated, as appears in Figure 2 or Figure 4, since the center of the shoe is of T-section. The above-described construction forms a channel-shaped pocket at each end of the shoe, overlapping the end of the adjacent shoe 14 or 18, and with the sides of the pocket overlapping shoe 14 projecting as mounting arms pivoted on the anchor 20 and offset within the curve of the shoe to clear the end of the friction portion of shoe 14.

While one very desirable construction has been described in detail, it is not my intention to limit the scope of the invention to that particular construction, or otherwise than by the terms of the appended claims.

I claim:

1. An arcuate brake shoe having a cylindrical friction portion and a stiffening web between the edges of the friction portion, at least a part of the stiffening web being Y-shaped in radial cross-section.

2. An arcuate brake shoe having a cylindrical friction portion and a stiffening web between the edges of the friction portion, at least a part of the stiffening web being Y-shaped in radial cross-section, with the stem of the Y adjacent the friction portion and with the two branches forming parts spaced from each other crosswise of the shoe.

3. An arcuate brake shoe having a cylindrical friction portion and a stiffening web between the edges of the friction portion, at least one end of the stiffening web being Y-shaped in radial cross-section, with the stem of the Y adjacent the friction portion of the shoe.

4. An arcuate brake shoe having a cylindrical friction portion and a stiffening web, the stiffening web and the friction portion jointly being T-shaped in radial cross-section in the central part of the shoe, and with the stiffening web at least at one end of the shoe branching to be Y-shaped in cross-section both radially and lengthwise of the shoe.

5. An arcuate brake shoe having a cylindrical friction portion and a stiffening web, the stiffening web and the friction portion jointly being T-shaped in radial cross-section in the central part of the shoe, and with the stiffening web at least at one end of the shoe Y-shaped in cross-section radially of the shoe.

6. An arcuate brake shoe having a cylind-

rical friction portion and a stiffening web, the stiffening web and the friction portion jointly being T-shaped in radial cross-section in the central part of the shoe, and with the stiffening web at both ends of the shoe branching to be Y-shaped in cross-section both radially and lengthwise of the shoe.

7. An arcuate brake shoe having a cylindrical friction portion and a stiffening web, the stiffening web and the friction portion jointly being T-shaped in radial cross-section in the central part of the shoe, and with the stiffening web at both ends of the shoe Y-shaped in cross-section radially of the shoe.

8. An arcuate brake shoe having a cylindrical friction portion and a stiffening web, the stiffening web at one end of the shoe being Y-shaped in radial cross-section with the stem adjacent the friction portion, and with the sides of the Y-section part of the web projecting beyond the end of the friction portion to form mounting arms.

9. An arcuate brake shoe having a cylindrical friction portion and a stiffening web, the stiffening web at one end of the shoe being Y-shaped in radial cross-section with the stem adjacent the friction portion, and with the sides of the Y-section part of the web projecting beyond the end of the friction portion to form mounting arms, the arms being offset within the curve of the shoe to straddle the end of an adjacent shoe and clear the end of the friction portion of said adjacent shoe.

10. An arcuate brake shoe of pressed metal parts including a cylindrical friction portion and two flanges jointly forming a stiffening web, said flanges for at least a part of the length of the shoe being in engagement immediately adjacent the friction portion and being spread apart from each other as they are continued inwardly radially of the shoe, to form at least a part of the web of Y-shape in radial cross-section.

11. An arcuate brake shoe of pressed metal parts including a cylindrical friction portion and two flanges jointly forming a stiffening web, said flanges at least at one end of the shoe being in engagement immediately adjacent the friction portion and being spread apart from each other as they are continued inwardly radially of the shoe, to form at least a part of the web of Y-shape in radial cross-section.

12. An arcuate brake shoe of pressed metal parts including a cylindrical friction portion and two flanges jointly forming a stiffening web, said flanges being in engagement with each other in the central part of the shoe and when taken with the friction portion being substantially T-shaped in radial cross-section, and at least at one

- end of the shoe being in engagement with each other immediately adjacent the friction portion and then spread apart to form a channel-shaped pocket at said end of the shoe.
13. An arcuate brake shoe of pressed metal parts including a cylindrical friction portion and two flanges jointly forming a stiffening web, said flanges being in engagement with each other in the central part of the shoe and when taken with the friction portion being substantially T-shaped in radial cross-section, and at both ends of the shoe being in engagement with each other immediately adjacent the friction portion and then spread apart to form a channel-shaped pocket, the sides of one of said pockets being continued as spaced mounting arms.
14. An arcuate brake shoe of pressed metal parts including a cylindrical friction portion and two flanges jointly forming a stiffening web, said flanges being in engagement with each other in the central part of the shoe and when taken with the friction portion being substantially T-shaped in radial cross-section, and at least at one end of the shoe being in engagement with each other immediately adjacent the friction portion and then spread apart to form a channel-shaped pocket at said end of the shoe, the flanges where they form the pocket sides being provided with bearings to engage pivoting means.
15. An arcuate brake shoe of pressed metal parts including a cylindrical friction portion and two flanges jointly forming a stiffening web, said flanges being in engagement with each other in the central part of the shoe and when taken with the friction portion being substantially T-shaped in radial cross-section, and at both ends of the shoe being in engagement with each other immediately adjacent the friction portion and then spread apart to form a channel-shaped pocket, the sides of one of said pockets being continued as spaced mounting arms, the flanges where they form the pocket sides being provided with bearings to engage pivoting means.
16. An arcuate brake shoe built up of two generally L-section stampings fastened back to back, with outer cylindrical flanges jointly forming the friction portion of the shoe, and with the inner flanges jointly forming a stiffening web, said stiffening web flanges at least for part of the length of the shoe being spread apart some distance inside of the friction portion to form a channel-shaped pocket.
17. An arcuate brake shoe built up of two generally L-section stampings fastened back to back, with outer cylindrical flanges jointly forming the friction portion of the shoe, and with the inner flanges jointly forming a stiffening web, said stiffening web flanges at least at one end of the shoe being spread apart some distance inside of the friction portion to form a channel-shaped pocket.
18. An arcuate brake shoe built up of two generally L-section stampings fastened back to back, with outer cylindrical flanges jointly forming the friction portion of the shoe, and with the inner flanges jointly forming a stiffening web, said stiffening web flanges at both ends of the shoe being spread apart some distance inside of the friction portion to form channel-shaped pockets.
19. An arcuate brake shoe built up of two generally L-section stampings fastened back to back, with outer cylindrical flanges jointly forming the friction portion of the shoe, and with the inner flanges jointly forming a stiffening web, said stiffening web flanges at least at one end of the shoe being spread apart some distance inside of the friction portion to form a channel-shaped pocket, and with the flanges forming the sides of said pocket projecting beyond the end of the friction portion to form spaced mounting arms.

In testimony whereof, I have hereunto signed my name.

LUDGER E. LA BRIE.
